UNITED STATES PATENT OFFICE

112,681

DESIGN FOR A FISH LURE BODY

Karl R. Larson, Minneapolis, Minn.

Application September 16, 1938, Serial No. 79,936

Term of patent 14 years

To all whom it may concern:

Be it known that I, Karl R. Larson, a citizen of the United States, residing at Minneapolis, in the county of Hennepin and State of Minnesota, have invented a new, original, and ornamental Design for a Fish Lure Body, of which the following is a specification, reference being had to the accompanying drawing, forming part thereof.

Fig. 1 shows the fish lure body in enlarged perspective looking downwardly on the top thereof;

Fig. 2 is a plan view of the fish lure body;

Fig. 3 is a side elevation of the same; and

Fig. 4 is a section taken on the line 4—4 of Fig. 1.

The design formed on the under surface of the lure body is visible through the material of the body. The front end of the lure body is designed to form a nose in which eyes in the form of crystals are inserted.

I claim:

The ornamental design for a fish lure body, as shown and described.

KARL R. LARSON,
